UNITED STATES PATENT OFFICE.

WILLIAM T. FAUST, OF BROWERVILLE, MINNESOTA.

BROODER.

978,010.

Specification of Letters Patent.

Patented Dec. 6, 1910.

Application filed July 9, 1909. Serial No. 506,775.

To all whom it may concern:

Be it known that I, WILLIAM T. FAUST, a citizen of the United States, residing at Browerville, in the county of Todd and State of Minnesota, have invented new and useful Improvements in Brooders, of which the following is a specification.

This invention relates to brooders, the object of the invention being to provide a simple, inexpensive and efficient construction of brooder which may be taken apart for package in close compass for storage or shipment, which embodies a novel construction and arrangement of doors for closing or opening the doorway of the brooder to different degrees, and in which novel means are provided for feeding and watering the hen and chicks.

The invention consists of the features of construction, combination and arrangement of parts hereinafter fully described and claimed, reference being had to the accompanying drawings, in which:—

Figure 1 is a perspective view of a brooder constructed in accordance with my invention. Fig. 2 is a vertical front to rear section through the same. Fig. 3 is a vertical transverse section on line 3—3 of Fig. 2. Fig. 4 is a perspective view of the watering trough. Fig. 5 is a section on line 5—5 of Fig. 3. Fig. 6 is a cross section through one of the feed boxes. Fig. 7 is a horizontal section on line 7—7 of Fig. 2.

The body of the brooder is preferably of rectangular or oblong rectangular form and made of detachable sections of sheet metal, although it may be made of other suitable material. It comprises a bottom 1, side walls 2, a front wall 3 and a rear wall 4. The bottom wall is provided at each of its edges with a depending flange 5. The side flanges of this wall are slidably engaged by the lower hooked or channeled edges 6 of the side walls, which latter are provided at their upper edges with outturned flanges 7 and 8 and at their front and rear edges with hooked flanges 9 and 10. The edges 9 are engaged by the hooked edges 11 of the front wall, which latter bears at its lower edge against the front flange of the base of the bottom wall and is provided with a rearwardly turned flange 12 extending beneath the same and formed at its upper edge with a forwardly projecting flange 13. The rear wall bears at its lower edge against the rear flange of the bottom wall and is provided

with a rearwardly extending flange 14, while the upper edge of said rear wall is formed with a forwardly extending inclined flange 15. The rear wall is relatively shorter than the front wall and the upper edges of the side walls are inclined to support the top or cover 16 at a downward or rearward slope or angle to form a rain shed. The cover is provided at its side edges with hooked flanges 17 to engage the flanges 7 of the side walls, and at its front edge with a hooked flange 18 to engage the flange 13 of the front wall, while the rear edge 19 of the cover is downwardly bent and extends sufficiently beyond the rear wall to coöperate with the flange 15 in preventing access of rain water at this point and to form a perfect shed.

It will be seen from the foregoing description that the parts of the brooder thus far described are slidably connected, so that they may be conveniently assembled and disassembled, allowing the brooder to be taken apart and packed in close compass for storage or transportation when occasion requires. The arrangement of the base flanges of the walls adapts the lower hooked edges of the side walls, the base flange of the front wall, the front flange of the bottom wall and the base flange of the rear wall to lie in the same plane and rest upon the ground or floor to firmly and stably support the brooder.

The side walls are provided with hand loops or grips 20 by which the set up brooder may be conveniently lifted and transported, and one of said side walls is slotted to provide ventilation openings 21 and deflectors or partial closures 22 therefor, by which a sufficient amount of air is permitted to enter the brooder to keep the interior atmosphere in a wholesome condition.

A doorway 23 is provided in the front wall for the entrance and exit of the brood hen and chicks, and arranged horizontally across the front wall above and below the line of the doorway are channeled strips 24 and 25 forming guideways, the upper strip being provided at each end with a downwardly bent stop portion 26. Mounted for sliding movement at their upper and lower edges in the guideways are doors 27, 28 and 29. The door 27 consists of an imperforate body of sheet metal or other material of sufficient size to wholly close the doorway, and it is provided at one of its side edges with a flange 27' forming a stop and finger

piece. The door 28 consists of a body of wire or reticulated material of comparatively close mesh and is provided at one of its side edges with a similar flange 28' forming 5 a stop and finger piece. It will be understood that the door 27 when closed seals the doorway against the entrance of air and light and the passage of the hen and chicks, while the door 28 when closed permits of 10 the passage of air and light, while preventing the passage of the hen and chicks. The door 29 consists of a grating having spaces between its portions sufficiently large for the passage of the chicks, while preventing passage of the hen, which may be confined 15 within the brooder without closing the doorway against the ingress and egress of the chicks when they are allowed to run. As shown, the door or grating 29 is preferably 20 composed of upper and lower strips 30 to which are fastened a series of spaced rods or pickets 31, the ends 30' of the strips 30 facing the flange 28' of the door 28 being outwardly curved to bear against the outer 25 sides of the guideways and to permit passage of the intermediate door 28 without interference. By the use of this series of doors the doorway may be controlled as occasion or circumstances may require. By 30 the use of the door 28 perfect ventilation may be afforded in warm weather while closing the doorway against the access of canines, rodents and other animals. All 35 three doors may be closed when perfect security is desired.

The rear wall is provided with an opening 32 and a series of openings 33, the former being of greater height than the latter, and arranged above these openings across the 40 wall is a hooked supporting strip 34. A watering trough is provided and comprises a tank 35 closed against the entrance of air except at its lower forward end where it is provided with an outlet opening 36. 45 This opening communicates with a well or drinking chamber 37 on the lower front portion of the box, on which latter is also arranged a curved guard 38 overhanging the inner portion of the well. The well and 50 guard are adapted to project through the opening 32 into the brooder, the well resting upon the bottom wall 1 to assist in supporting the trough in position. The trough is provided with a hooked suspending flange 55 39 at its upper forward edge to engage the hooked supporting strip 34, by which it is detachably suspended in position for use and in such manner as to permit of its ready removal. The function of the guard 38 is 60 to prevent the hen from stepping into the well while permitting her to insert her head to drink. The trough is filled while turned back to a horizontal position through the well 37 and opening 36, so that when it is 65 restored to a vertical position the pressure

of the air from without on the surface of the body of water in the well will maintain the water therein at a desired level and permit a sufficient amount to feed from the trough to compensate for that consumed and 70 that lost by evaporation. At the sides of the opening 32 strips 40 are arranged and form guideways for a sliding door, not shown, which may be applied to close the opening while the removed trough is being refilled. 75 The openings 33 are designed to receive wells or boxes 41 projecting forwardly from the lower ends of feed troughs 42, each of which troughs is formed with an outlet 43 for the feed by gravity of the food stuff 80 contained therein to the box 41 as it is gradually consumed.

The feed boxes are supported in a similar manner to the watering trough, each extending at its base through the opening 33 and 85 resting on the wall 1, and being provided at its upper forward edge with a hook 44 to engage the hooked supporting strip 34, whereby the feed troughs are detachably mounted in position. The upper edges of 90 the side walls of each feed trough are formed with outturned flanges 45, and the upper edge of the rear wall thereof with a flange 46. A cover plate 47 is provided to close the open top of the trough through which the 95 food is introduced, and this cover is provided with hooked side edges 48 to engage the flanges 45 and with a rear hooked edge 49 to engage the flange 46, by which the cover may be applied and removed in an 100 obvious manner.

From the foregoing description, taken in connection with the accompanying drawings, the construction and mode of use of my improved brooder will be readily understood, 105 and it will be seen that the invention provides a simple construction of brooder of the take-apart type which may be readily assembled for use and disassembled for package in close compass for storage or transportation. Also it will be seen that the construction disclosed provides substantial advantages in the control of the doorway and supply of food and drink.

A guard 50 is secured to the rear wall 4 to 115 overhang the wells of the watering and feed troughs to permit the hen to insert her head beneath the same and into the wells, while preventing her from stepping into the wells and scattering the water and food.

I claim:—

1. A brooder comprising a bottom wall having depending flanges at its front, rear and side edges, side walls having outwardly extending flanges of their upper edges and 125 hooked flanges at their front, rear and lower edges, the latter engaging the side flanges of the bottom wall, front and rear walls having respectively outwardly, and inwardly extending flanges at their upper 130

edges and hooked flanges at their side edges engaging the front and rear flanges of the side walls, and a top wall adapted to rest upon the flanges at the upper edges of the 5 front and rear walls and having side flanges engaging the flanges at the upper edges of the side walls, and a rear down bent flange overhanging and projecting beyond the inwardly bent flange at the upper edge of the 10 rear wall.

2. A brooder having a doorway, guides above and below the doorway, and inner, intermediate and outer doors arranged for movement in said guides in parallel relation, 15 the inner door being imperforate, the intermediate door having openings of a certain size, and the outer door having openings of a different size, said inner and intermediate doors having outwardly bent finger pieces 20 at one side and said outer door having outwardly bent flanges at its opposite sides, the said flanges and finger pieces of the doors frictionally engaging the outer walls of the guideways.

25 3. A brooder provided in one of its walls with an opening, a hooked retaining strip upon the exterior of said wall above said opening, an inclined guard upon the interior

of said wall above the opening, a receptacle having a discharge outlet at its lower end 30 and a downwardly extending hooked flange at its upper forward edge to engage said retaining strip, and provided with a well or open compartment communicating with said outlet and adapted to extend into the brood 35 chamber through the opening in said wall and below said inclined guard.

4. A brooder having one of its walls provided with a plurality of openings, a hooked supporting strip upon the exterior of said 40 wall extending lengthwise above said opening, a downwardly inclined guard upon the inner side of the wall also extending lengthwise above the openings, and a plurality of receptacles each having a downwardly projecting flange at its upper front edge to engage said strip and provided with wells 45 adapted to project through the opening into the brooder and below said inclined guard.

In testimony whereof I affix my signature 50 in presence of two witnesses.

WILLIAM T. FAUST.
